RUPTURE HOLDER

William M. Nix, Lakeland, Fla.

Application August 21, 1941, Serial No. 407,813

7 Claims. (Cl. 128—107)

This invention aims to provide a truss pad frame which will cause the wearer a minimum amount of discomfort, the article being inexpensive and durable. The invention aims, further, to provide novel means for holding the truss pad frame and associated parts in proper position on the body of a wearer.

Fig. 1 is a perspective view showing a device constructed in accordance with the invention, adapted for use in retaining a groin rupture, Fig. 2 is a section on the line 2—2 of Fig. 1, Fig. 3 is an elevation showing a modification, Fig. 4 is an elevation disclosing the opposite side of the modified form from that displayed in Fig. 3, Fig. 5 is a section on the line 5—5 of Fig. 3, and Fig. 6 is a section on the line 6—6 of Fig. 4.

Referring to the groin rupture truss of Figs. 1 and 2, there is supplied a body-engaging member, such as a belt 1, made of flexible or resilient material, having its ends united at the front by a strap and buckle 6, or in any other suitable way. The rear end of a flexible or resilient perineal strap 2 is attached to the belt 1, the forward end of the strap being provided with one part of a separable fastener, such as a pair of eyes 3. A flexible anchor strip, made of leather or the like, extends lengthwise of the belt 1, at the front of the belt, and is marked by the numeral 4, the end portions of the anchor strip being secured at 5 to the belt. The anchor strip 4 is long enough so that it offsets a little from the belt 1, or shown in Fig. 2, to provide for the insertion of parts hereinafter described.

A frame forms parts of the invention and embodies a U-shaped member 7, which may be made of strong and resilient wire. At their upper ends, the side arms of the resilient member 7 are formed into depending hooks 8. At their lower ends, the bills of the hooks 8 are extended laterally and are twisted together to form a brace 9, having unusual strength, and preventing the bills of the hooks from springing toward or from each other. The extension of the bill of each hook 8 may be formed into an eye 10, embracing the bill of the other hook closely.

The resilient member 7, including the upper portions of the hooks 8, is enclosed within a tubular covering 11, preferably made of rubber or a rubber composition. In its bottom portion, the resilient frame member 7 is formed into a pair of hooks 12, extended outwardly through the openings in the covering 11, and adapted to be engaged by the eyes 3 of the perineal strap 2, the hooks 12 being joined by an integral connecting

portion 14 of the frame member 7, located outside the covering 11, as Figs. 1 and 2 show.

The frame 7—11 is pushed downwardly between the offset anchor strip 4 and the front part of the belt 1, to the position of Fig. 2, so that the hooks 8 engage over the upper edge of the strip. Since the bends of the hooks 8 are covered, they will not cut downwardly into the strip 4. The tubular covering 11 acts as a cushion and prevents the frame member 7 from giving the wearer discomfort.

The space within the frame 7—11 is bridged by the garments (not shown) of the wearer and the rupture is retained adequately. Because the covering 11 is made of rubber, it has a good frictional hold on the garments, and the part of the garments that is within the contour of the frame 7—11 will not shift about on the rupture, or become too slack.

20 The U-shaped resilient member 7 and the friction covering 11 are shaped to conform to the margin of the rupture to be retained: meaning thereby that the opening within the contour of the part 7—11 is about equal in size to the outer end or mouth of the opening from which the rupture protrudes. Clearly, it would be a disadvantage to have the garments pressed to the body in markedly spaced relation to the margin of the rupture, because thereby an unnecessary amount 25 of the garments would be exposed for stretching.

If an ordinary rupture not of the groin type is to be retained, recourse is had to the form shown in Figs. 3 to 6.

30 The body member of the frame, corresponding 35 in function and in material to the member 7, is marked by the numeral 15, and is in the form of a continuous ring. The body member 15 is enclosed in a tubular, annular covering 16, corresponding in function and in material to the covering 11.

40 The ends of an anchor strip 17, made of tape or the like, are looped about the covering 16 and are connected to the body part of the anchor strip, as shown at 18. A body engaging member, such as a belt 19, is threaded between anchor strip 17 and the covering 16 of the frame.

45 The numeral 20 marks a retaining strip, made of textile ribbon or the like, and having its ends 21 secured about the covering 16 of the frame. The retaining strip 20 is located in one diameter 50 of the frame 15—20, the anchor strip 17 being disposed in another diameter of the frame, at right angles to the first mentioned diameter. The strips 17 and 20 are disposed on opposite sides of the frame 15—20, as Fig. 6 displays.

55 A pad 22, fashioned from any appropriate soft

and resilient material, is located between the strip 20 and the belt 19, the pad fitting closely but removably within the contour of the frame 15-20. Figure 4 shows the face of the pad 22 that is disposed against the rupture. The retaining strip 20 is made of soft material and is very thin. It will not irritate the rupture, and users will not be aware of its presence, whilst the truss is being worn.

The device, in either of its forms, has the advantages hereinbefore pointed out. A mechanic who abides by what is claimed, can make changes in the precise structures shown, without departing from the spirit of the invention.

Having thus described the invention, what is claimed is:

1. In a truss, a U-frame shaped to conform to the margin of the rupture to be retained, the upper portions of the side arms of the frame terminating in means for assembly with a body-engaging support, the lower bend of the frame being provided with a device for engagement with a perineal strap.

2. In a truss, the structure specified in claim 1, and wherein said means embodies downwardly-opening hooks.

3. In a truss, the structure specified in claim 1, and wherein said means embodies downwardly-opening hooks, and a connection joining the bills of the hooks.

4. In a truss, the structure specified in claim 1, and wherein said means embodies downwardly-opening hooks, the lower portions of the bills of

the hooks merging into lateral extensions which are twisted together for reinforcement, and means for joining the end of the extension of each hook to the side arm of the other hook.

5. In a truss, an approximately U-shaped frame member, formed to conform to the margin of the rupture to be retained, the upper portions of the side arms of the frame member terminating in downwardly-opening hooks, a connection joining the lower ends of the bills of the hooks, a tubular cushion mounted on the frame member and extended upon the bills of the hooks, a portion of the frame member extending outwardly through the cushion, at the bottom of the frame member, and shaped for assembly with a perineal strap.

6. In a truss, a tubular, centrally-open, covering, shaped to conform to the margin of the rupture to be retained, and a reinforcing frame member extended through the bore of the covering, a portion of the frame member extending out of the upper part of the covering, and being shaped for connection with a body-engaging support.

7. In a truss, a tubular, centrally-open, covering, shaped to conform to the margin of the rupture to be retained, and a reinforcing frame member extended through the bore of the covering, a portion of the frame member extending out of the lower part of the covering, and being shaped for connection with a perineal strap.

WILLIAM M. NIX.
